UNITED STATES PATENT OFFICE

GUY CARPENTER, OF NEW YORK, N. Y.

SPARK AND CINDER ARRESTER FOR STEAM ENGINES

Application filed February 16, 1924. Serial No. 693,185.

My invention relates to the art of steam engines, in which devices to arrest and collect the sparks and cinders, are to be used and has for its principal object to provide a device of this character which will successfully and completely collect and retain all minute particles, which are ordinarily thrown off and emitted through the stack, in proper chambers within the engine. These substances, when cooled, may be discharged from the collecting chamber, or, if desired, they may be placed back in the fire box and again used for combustion.

Sparks which are emitted through the stack of an engine are not only a great nuisance on account of creating dirty conditions, but are a great menace to public safety in that they frequently cause very disastrous fires, particularly along the road of a railway, and for those reasons precautions should be taken to arrest their progress and collect them into a chamber from which they may easily and quickly be removed and either discarded as waste, or utilized again as fuel. It is to such purposes my invention is directed and my object is to produce such a device in a simple, durable and strong construction that can, at a very reasonable expense, be fitted to any steam engine of the usual type of construction now in use.

I attain my objects by causing the products—the cinders and sparks—to attain a velocity and follow a path which will cause the particles of solid matter to be expelled by centrifugal action and finally be deposited in a collecting chamber, as will be more fully understood by reference to the drawings forming a part of this specification in which:

Fig. 1 shows a longitudinal sectional view of the forward part of a locomotive to which is added an extension of the smoke-box which contains most of the functioning elements of my device.

Fig. 2 is a transverse sectional view of the smoke-box and contents, taken on the line 2—2, in Fig. 1.

Fig. 3 is a detail view of the inner cylinder and attached spiral I employ, and

Figs. 4 and 5 are detail views showing a baffle and its attendant openings through the

cylinder, which constitute an important element of my device.

Referring to the accompanying drawings, the reference numeral 10 is used to indicate the smoke-box of a locomotive which I employ and which, preferably, extends further forward than ordinary smoke-boxes now in use. The smoke-box for my purposes may be constructed and attached to the present type locomotives as an extension, secured thereto in any suitable manner, and arranged at the front end to receive the front end connections of the locomotive. The numeral 11 indicates a cylinder, smaller than the smoke-box and preferably mounted therein in such a manner as to provide an annular space either concentric or eccentric between the outer surface of the cylinder and the inner surface of the smoke-box, the wider portion of the annular space when eccentrically mounted being located at the base of the cylinder. The rear end of the cylinder 11 is in close proximity to the stack chamber and is completely closed therefrom by a division plate 12 which is perforated centrally to receive an open end of a central cylinder 13 mounted therein. The front end of this cylinder 13 is also open and the cylinder does not project forwardly as far as the end of the smoke box.

A helically formed member 14 surrounds, and is secured to, the inner cylinder 13, its outer end contacting the inner wall of the cylinder 11, its front end being open so as to communicate with a chamber formed in the smoke box in advance of the cylinder 13. A screen 15 is secured to the forward end of the inner cylinder 13 and extends to the inner wall of the cylinder 11, and as it is also positioned in advance of the helically formed member, it is apparent a chamber is formed by the forward section of the smoke box and the screen and that the inner cylinder 13, open at its forward end communicates with this chamber.

The inner surface of the cylinder 11 is provided, at selected points, with baffles 16 which are positioned to oppose the direction of the flow of gases, the purpose of these baffles being to catch any solid particles re-

volving around the inner surface of the cylinder. Slots, or orifices, 17, extend through the cylinder 11, the baffles paralleling the said slots, the purpose of the slots being to 5 permit the solids striking the baffles to pass through the cylinder into the eccentrically shaped space between the cylinder and the inner surface of the smoke box.

The blades of the helically formed member 14 are preferably inclined rearwardly but 10 may be positioned at right angles to the axis of the cylinder, or even inclined slightly forwardly, if desired.

The numeral 18 indicates the stack and 19 the stack chamber which has its base above 15 the plane of the base of the cylinder 11 and an exhaust jet 20 extends from the bottom of the smoke box upwardly through the base of the stack chamber, said jet being obviously 20 positioned centrally below the open bottom of the stack 18. By this construction, as clearly shown by the drawings, a chamber is formed which leads from the fire tubes 21, below the stack chamber 19 and opening into 25 the lower portion of the cylinder 11, in which the inner cylinder 13 and the helically formed member 14 are located. Through the chamber thus formed, the gases from the fire tubes flow into the cylinder 11, and as 30 sume a rotary motion, in passing around the cylinder 13, by striking the helically formed member and finally they are discharged through the screen 15 into the chamber at the forward part of the smoke box and sucked 35 back through the inner cylinder 13 to the stack chamber and finally discharged through the stack.

As the velocities produced by the action of the jet 20 (being the ordinary action produced by the usual functioning of the jet) are 40 very high, the gases in passing through the helically formed member are revolving at extremely high velocity, thus creating a strong centrifugal force which acts upon the 45 particles of solids, such as cinders, sparks and the like, in the products of combustion, and they are, consequently, thrown outward against the inner surface of the cylinder 11, caught by the baffles and conducted through 50 the openings into the annular space between the cylinder 11 and the inner surface of the smoke box and fall to the bottom thereof. In the base of the smoke box I have provided 55 a door 22, through which the solids, dropping in this chamber formed between the outer surface of the cylinder 11 and the inner surface of the smoke box and which chamber I style a "collecting chamber" may be cleaned out.

60 It is the utilization of the centrifugal action for this purpose (and which is assured by my construction) which constitutes one of the principal objects of my invention. The centrifugal action thus created is capable of 65 attaining great proportions which tends to

make sure of the separation of the solids from the gases and has, furthermore, the advantage of not causing any reversal of flow which would seriously impede the draft and cause a loss thereof. Another great advantage of my 70 construction is that the length of the path of the gases from the fire tubes to the stack is materially increased thereby giving the sparks and solids a longer time to cool so that if any of them should pass through the screen 75 15 they would be much less liable to set fire to surrounding objects. However the function of the screen is to prevent any sparks or solids from being discharged through the stack.

Having thus described my invention, what I claim and desire to secure by Letters Patent of the United States is:

1. A spark arrester for locomotives employing a fire box, comprising a smoke stack; a smoke box; a horizontally disposed cylinder, provided with openings through the wall thereof, mounted in the smoke box, in advance of the smoke stack; baffles on the inner wall of said cylinder, one baffle being adjacent each of the said openings; an inner cylinder, centrally mounted within the first mentioned cylinder; a helically formed member, mounted between the inner wall of the outer cylinder and the outer wall of the inner cylinder; and a screen mounted between the two cylinders, and positioned in advance of the helically formed member. 90

2. A spark arrester for locomotives employing a fire box, comprising a smoke stack; a smoke box; a cylinder, provided with openings through its wall, mounted in said smoke box; a helically formed member, provided with an opening through the center thereof, horizontally and centrally disposed in said cylinder, a second cylinder in said opening, thereby forming a spiral passage between said cylinders; baffles on the inner surface of the first named cylinder, one baffle being positioned near each opening in the wall of said first named cylinder; a screen mounted in the forward end of the first named cylinder, and interposed between the helically formed member and the smoke box. 100

3. A spark arrester for locomotives employing a fire box, comprising a smoke stack, a smoke box, a cylinder, provided with a plurality of openings in its wall, mounted within the smoke box; a division plate between the cylinder and the smoke stack; an inner cylinder, provided with open ends, mounted in the aforesaid cylinder, the rear end of the inner cylinder extending through the division plate to a position near the smoke stack, the forward ends of the cylinders being adjacent the forward wall of the smoke box; baffles on the inner surface of the first mentioned cylinder, one of said baffles being positioned parallel to and adjacent each of the aforesaid openings; a helically formed member 115
